UNITED STATES PATENT OFFICE.

RICHARD TRUSWELL, OF TRAIL, BRITISH COLUMBIA, CANADA.

MACHINE FOR CASTING ANODE-PLATES.

974,541.

Specification of Letters Patent.

Patented Nov. 1, 1910.

Application filed August 27, 1909. Serial No. 514,911.

To all whom it may concern:

Be it known that I, RICHARD TRUSWELL, residing at Trail, in the Province of British Columbia and Dominion of Canada, have 5 invented new and useful Improvements in Machines for Casting Anode-Plates, of which the following is a specification.

My invention which will be hereinafter fully set forth and claimed relates to applications for casting anode-plates, such as are used in electrolytic processes of refining metals and objects of a similar character made of soft metal, such as lead and copper.

The object of my invention is a machine 15 that will work automatically and rapidly and with molds that are less subject to breakage from expansion and contraction.

Figure 1 is a plan of my improved machine. Fig. 2 is a vertical transverse section of the same. Fig. 3 is a face view of one of the molds on a larger scale. Fig. 4 is a longitudinal section of the mold on line 20 4—4, Fig. 3, partly in elevation. Fig. 5 is a transverse section of the same, on line 25 5—5, Fig. 3, and Fig. 6 is a view of the plate or anode produced by the machine.

Upon a suitable foundation, such as the base plate A, is secured a vertical stud or axle, B, upon which is journaled a large 30 bevel wheel, C, gearing into a pinion, D, which is fast upon a driven shaft, D¹, journaled upon said base and below the bevel wheel C. Radial arms, C¹, are secured upon the bevel wheel C which, at their 35 outer extremities, carry brackets. These brackets may be of any suitable description, but in the construction illustrated, they consist each of a vertical post, E, a horizontal outward projecting member, E¹, an inner 40 brace, E², secured to the arm C¹ and an outer bracket, E³, supporting the horizontal limb. Each arm carries a pair of these brackets, diverging as shown in Fig. 1. An annular plate, F, is secured upon these 45 brackets, above the post E; thus forming with the brackets, arms C¹ and wheel C a rigid horizontal table having a rotary motion in the direction shown by the arrow in Fig. 1. As this table is required to be very 50 rigid and steady, the posts E may be prolonged downward and bear upon a track, A¹, by means of a sliding foot, e or friction roller. The track A¹ may be integral with or be secured to the base A. The floor, a, 55 under the base is inclined preferably toward the center, and a drain, A⁰, is pro-

vided to carry off the water used in spraying and cooling. The brackets E E¹ at their outer extremities carry bearings, E⁴, adapted to receive the trunnions of the 60 molds. A mold is placed between each two arms C¹ and the brackets E E¹ adjacent to each mold are disposed parallel and close to it, one on each side.

The molds, G, are each composed of three 65 parts, as shown in Figs. 3, 4 and 5 and are adapted to what is known as open casting, i. e., held flat or in a horizontal position, open at the top and adapted to form the anode H. The main or body part is in two 70 sections, 2 and 3, joined longitudinally and medially with a tongue-and-groove joint, 5, and held together by bolts, G¹, which may pass through the plate and have springs, G², inserted between the sides and the heads and 75 nuts—the springs compensating for expansion and contraction. A rim, g, runs around one end and both sides, determining the thickness of the plate to be cast. Trunnions, g¹, may be integral with and project from 80 the sides, their axis placed between the center of gravity of the finished plate and its head, so that the plain end is heavier than the head end. The trunnions g¹ are journaled in the bearings E⁴ on the brackets and 85 this part of the mold is thus pivotally mounted. The head section, 4, is separate; it is joined to the main part with a beveled joint, 6, sloping from the face to the back and from the head toward the bottom—adapted 90 to allow the swiveling section, 2, 3, to part readily from the head section 4, which is fast upon the annular plate F and to swing its beveled end upward. The swivel parts of the molds are kept raised in a horizontal 95 position and joined to the heads by a rail, I, extending part around the circle, secured to the base and upon which the back of the molds bear. The ends of this rail are curved, one, i, Fig. 1, which the molds meet first in 100 the course of the rotation, inward, so as to engage the back of the hanging molds and raise them in position ready for filling; the other end, i¹, Figs. 1 and 2, curved downward to allow the molds to tilt.

J indicates the spout or filler; it discharges upon the mold that has been first raised into position.

K is a perforated water pipe, nearly co-extensive with the rail I and adapted to 110 spray the back of the filled molds with water and cool them.

To prevent the tilting section of the mold from failing to upset after leaving the rail I, a pulley L, acting like an inclined plane cam, is journaled in a suitable bracket, L¹, secured to the base plate A, which pulley engages the mold and forces it down.

The device operates as follows: The wheel C turning in the direction of the arrow, Fig. 1 with the arms C¹, turning in the direction of the arrow, Fig. 1, brackets E and plate F, forms a horizontal rotary table on which the open molds G are hung on trunnions, held flat and making joint with the fixed heads for filling by sliding upon a circular rail. This rail I which by its curved end i first picks up the depending end of the mold, holds the latter flat and steady while passing under the filler J and until it reaches the tilting device i¹ and L. The filled mold, always in motion, moves on and passes over the spray pipe, the metal in it cooling and setting until it arrives at the point where the rail I dips. The mold is now free to tilt, upset and dump the casting, the pulley L assisting in the latter operation and thus the casting is removed. In tilting, the main part of the casting H lifts the head from the fixed head part of the mold. After upsetting, the mold remains suspended until the end i of the rail picks it up again and it is tilted up back into position ready for filling again.

The mold being in three pieces and two of them yieldingly connected, while the head parts from them at a plain joint, reduces the tendency to crack from unequal expansion and contraction to a minimum.

It will be selfevident that the shape of the casting produced by this machine is not confined to the shape of the anode H shown and that the shape of the mold will, of course, vary with that of the desired casting.

I claim as my invention:

1. In a casting machine, the combination with a base of a vertical axle, a bevel wheel journaled upon said axle, a bevel pinion gearing into said bevel wheel, an axle journaled upon said base and carrying said pinion, radial arms secured upon said wheel, a pair of brackets secured upon the free end of each of said arms, an annular plate secured upon said brackets, a bearing secured upon each bracket, a mold head secured upon said plate between each pair of arms, an open swivel section mold with trunnions journaled in said bearings and making joint with the head section, a rail with curved ends extending partly around the circle and

supporting some of the swivel sections of said molds, a spray pipe nearly coextensive with said rail, and a pulley under which the outer ends of the molds have to pass after leaving said rail, substantially as set forth.

2. In a casting machine, the combination with a base, of a horizontal bevel wheel journaled thereon, a bevel pinion geared in said wheel, a shaft carrying said pinion, radial arms secured to said wheel, a pair of brackets at the end of each arm, an annular plate secured upon said brackets, a bearing at the projecting end of each bracket, a mold head secured upon said plate between each pair of arms, an open swivel mold section with trunnions journaled in the bearings of the brackets and making joint with the head and a horizontal circular rail with curved ends extending partly around the circle under and supporting some of the pivoted sections of the molds, substantially as set forth.

3. In a casting machine, the combination with a base of a horizontal rotary table mounted thereon, means of giving a rotary motion to said table, a series of pairs of horizontal bearings on the periphery of said table, a mold-section with trunnions journaled in each pair of bearings, a head section of the mold secured to the table adjacent to each pivoted section and making joint therewith and a horizontal circular rail with curved ends extending under and supporting some of the journaled sections, substantially as set forth.

4. In a casting machine mold, the combination of a plate divided longitudinally and joined with a tongue-and groove joint, bolts placed transversely to said joint, a coiled spring upon the ends of said bolts extending between the sides of the plate and the head and nut respectively, a rim on one end and two sides of said plate, a beveled edge on the other end of said plates, a trunnion on each side of said plate adapting it to be pivotally hung and upset, a head section conforming to said swivel section adapted to be fixed into position and provided with a beveled edge fitting the beveled edge of the swivel section and allowing the latter to swing upward, substantially as set forth.

In testimony whereof I have affixed my signature, in presence of two subscribing witnesses.

RICHARD TRUSWELL.
